CLAIM

The ornamental design for the AC contactor, as shown and described.

DESCRIPTION

FIG. 1 is a left side view of an AC contactor showing my new design;

FIG. 2 is a right side view thereof;

FIG. 3 is a rear elevational view thereof;

FIG. 4 is a front elevational view thereof;

FIG. 5 is a bottom view thereof; and,

FIG. 6 is a perspective view thereof.

The broken line portion of the figure drawings is included to show unclaimed subject matter only and forms no part of the claimed design.
